CLAIM

The ornamental design for a medicament injector, as shown and described.

DESCRIPTION

FIG. 1 is a front and top left perspective view of a medicament injector showing our new design;
FIG. 2 is a front elevational view thereof, shown at its operative maximum extended length;
FIG. 3 is a front elevational view thereof, shown at its operative minimum, compressed length;
FIG. 4 is a rear elevational view thereof;
FIG. 5 is a top plan view thereof, the bottom plan being a mirror image thereof;
FIG. 6 is a left side elevational view thereof; and
FIG. 7 is a right side elevational view thereof.

FIG. 1

FIG. 6

FIG. 7

FIG. 2

FIG. 3

FIG. 4
